ROUGH ROUNDING AND CHANNELING
MACHINE

Harold Ernest Elliott, Harold John George, and
Arthur Alan Rivington, Leicester, England, as-
signors to United Shoe Machinery Corporation,
Flemington, N. J., a corporation of New Jersey

Application January 5, 1951, Serial No. 204,516
In Great Britain January 14, 1950

10 Claims. (Cl. 12—18)

1

This invention relates to improvements in machines for rough rounding and channeling the soles of shoes, and is illustrated herein as embodied in a machine of this type as disclosed in Letters Patent of the United States No. 2,209,377, granted on July 30, 1940, upon an application of C. M. Bagshaw et al.

As in the case of the prior Bagshaw machine the present machine is intended, by virtue of its low cost, simplicity, and adjustability, to be adapted particularly for use by shoe repairers, whose work is varied in regard to the types of shoes operated upon, and who, in most cases, do not have the high degree of skill required by the usual rounding and channeling machines used by shoe manufacturers.

The illustrative machine includes structure, commonly employed in rounding and channeling machines, comprising means for feeding the work with a step-by-step movement, a chopping knife for trimming the sole, a channeling knife, and a work rest or guide for supporting the shoe and positioning it in the desired relation to the chopping and channeling knife. An object of the invention is to provide an improved machine of this type with a view to obtaining the greatest possible steadiness in the support and feeding action of the work while it is being operated upon.

To this end, and in accordance with one feature of the invention, the work rest and feeding means of the illustrated machine cooperate to support the work continuously at the same level, this result being obtained by mounting the feeding means for movement in the same plane in which the work is supported by the work rest. The above-mentioned feeding means comprises an anvil against which the chopping knife cuts, and a feed foot which not only constantly grips the work against the anvil, but also is mounted to move with the anvil throughout its feeding and return movements. Serrated work engaging surfaces upon the anvil and feed foot cause the work to be effectively gripped during their feeding movement, and yet permit them to slide freely upon the work during their return movement.

The channeling knife of the illustrated machine is mounted upon the feed foot with its cutting edge so directed that the channeling cut is made during the return stroke of the feed foot. In order to insure that the work will be held securely against back-feeding at this time, the work is gripped by means separate from the feeding means during each return stroke of the feeding means. To this end, and in accordance with another feature of the invention, the illustrated

5 machine also comprises a presser foot which grips the work against the above-mentioned work rest in advance of the point where it is operated upon by the chopping knife, the pressure of the presser foot upon the work being relieved during each feeding movement of the feeding means whereby any drag tending to impair the feeding action of the feeding means is eliminated.

10 Invention is also to be recognized in a quick-release mounting for the feed foot by which a fine adjustment of the channeling knife may be obtained, and which permits the replacement of the feed foot in the machine in its former position of adjustment, after sharpening or replacement of the channeling knife, without any attention on the part of the operator.

15 The above and other features of the invention will now be described in detail with reference to the drawings, and will be defined in the appended claims.

20 In the drawings,

Fig. 1 is a front elevation of an illustrative machine embodying the invention;

25 Fig. 2 is an elevation of the machine as viewed from the left, a cover plate having been removed to expose the operating mechanism;

Fig. 3 is a rear elevation, parts of the machine having been broken away and shown in section; and

30 Fig. 4 is a plan view, a part of the frame of the machine having been broken away.

35 A shoe to be operated upon, and having had a repair sole temporarily attached to its bottom, is presented to the machine with the sole substantially horizontal. The shoe is positioned in the machine by a work rest 10 (Fig. 2) having a horizontal flange 12 which is adapted to be inserted between the welt of the shoe or its bottom and the sole. The work rest also comprises a vertical plate 14, integral with the flange, and adapted to act as a guide by engaging the edge of the welt, or the side of the shoe upper if the shoe has no welt. The work rest thus positions the shoe heightwise and crosswise of a vertically reciprocating rounding knife 16, which cuts

40 against an anvil 18 disposed immediately to the left of the work rest 10 and at the level of the flange 12. A feed foot 20 engages the bottom of the sole beneath the anvil 18 and constantly holds the sole against it. The anvil and feed foot are moved together to the left to impart a feeding movement to the work and then, after a dwell, during which the cutting stroke of the knife occurs, are returned to the right hand extremity 45 of their stroke. During each return stroke of

these feeding members a channeling knife 22, associated with the feed foot 20, makes a channeling cut in the sole, back feeding of the work being prevented during this time because it is gripped between a presser foot 24, which engages the bottom of the sole, and the flange 12. Just as the feeding movement of the feeding members begins, and throughout such movement, the presser foot is separated from the flange so as to minimize their resistance to the feeding of the work. Having broadly outlined the use and operation of the principal work-engaging elements of the machine its construction will now be described in detail.

The above-mentioned flange 12 has a serrated lower surface and is slightly tapered in thickness toward its forward edge which, as viewed in plan (Fig. 4), curves rearwardly toward the right of the machine. The plate or guide 14 projects upwardly from the rearward edge of the flange and, as viewed in plan, conforms generally to the curved shape of the flange and projects from the flange toward the left across the anvil 18, the left-hand extremity of the guide also being curved toward the rear of the machine. The work rest is carried by a bar 26 which is adjustable crosswise of the edge of the knife in a groove formed in the lower side of the head of the frame 28, and may be secured in any desired position of adjustment by setting up a clamp screw 30 which is vertically mounted in a boss 32 on the frame.

The presser foot 24 is adjustably fixed upon the forward notched end of a lever 34 which is mounted for swinging movement in a vertical plane to relieve the gripping pressure of the presser foot upon the work as described above. The presser foot has a round shank 36 which is received in a hole in the lever, permitting the presser foot to be adjusted forwardly and rearwardly of the machine. The presser foot is secured in adjusted position by a stud 38 which is notched to receive the shank 36, and is threaded into a nut 40 which may be set up against the side of the lever to lock these parts together.

The lever 34 extends to the rear of the machine where it is mounted to swing, about a horizontal axis, upon a stud 42 fixed to the frame. The lever also extends downwardly below the stud and carries at its lower end a pin 44 around which is hooked one end of a spring 46. The spring is stretched between the pin 44 and another pin 48 which is clamped in the end of an arm 50 which is mounted to swing upon a stud 52 fixed in the side of the frame. The pin 48 projects through an arcuate slot 54 formed in the right-hand side of the frame and carries a knob 56 which slides axially upon the pin and is yieldingly held in engagement with the side of the frame, the latter having notches 58 arranged to receive the shank of the knob whereby the lever 50 is held in whatever position into which it has been adjusted. It is evident that the spring 46 will cause the presser foot 24 to be urged upwardly with the greatest force when the spring is horizontal, as illustrated in Fig. 2, and that this pressure is diminished the higher the knob 56 is raised. This adjustment is useful to adapt the machine for operating upon various types of sole material. In the case of crepe rubber, for example, the use of a fairly light clamping pressure is required in order not to distort the sole.

The anvil 18 is mounted with its forward edge disposed somewhat rearwardly of the forward

extremity of the flange 12, its work engaging surface being level with that of the flange and also being serrated forwardly of that part which is engaged by the knife 16. The anvil has a dovetailed shank 60 (Figs. 1 and 4) which is received in a similarly shaped recess in the forward bifurcated end of an arm 62 in which the shank 60 is secured by a clamp screw 64. The arm 62 curves downwardly toward the rear of the machine and has integral therewith a sleeve 66 which is bored to receive a shaft 68 the ends of which are pivotally mounted in bosses 70, 72 which are integral with the frame. This mounting of the arm 62 permits the anvil 18 to swing laterally of the work rest in a horizontal plane, and the feed foot 20 always moves laterally with the anvil as will now be described.

The feed foot is mounted upon the forward end of an arm 74 which extends to the rear of the machine where it is mounted to swing upon a horizontal shaft 76 which is fixed in a bracket 78 formed integral with the sleeve 66. The arm 74 is constantly urged upwardly to cause the sole to be gripped between the feeding members 18, 20 by a spring 80, the upper end of which is seated in a recess in the lower side of the arm 74, and the lower end of which rests upon a lug 82 which is integral with the frame. The spring is held on the lug by a guide rod 84 which extends upwardly inside of the spring and is fixed to the lug. In order to prevent interference between the anvil, and the channeling knife or the presser foot, when no work is in the machine, upward movement of the arm 74 is limited by a screw 84 arranged to engage the upper side of the arm 74, and threaded in a lug 86 which projects laterally from the left-hand side of the arm 62. The feed foot may be lowered in order to facilitate presenting the work to the machine by depressing a treadle (not shown) which is connected by a rod 88 to a hook 90 which is secured to the arm 74. The presser foot 24 is lowered simultaneously with the feed foot owing to the provision of a lug 92 (Fig. 1) which extends from the arm 74 over a shoulder 93 on the arm 34 upon which the presser foot is mounted.

The feeding members are urged towards the left during their feeding movement by a spring 94 which is compressed between a pair of studs 96, 98 having rounded ends arranged to engage tapered seats formed in the arm 74 and a plug 100, respectively, the latter being threaded into the right-hand side of the frame. The adjacent ends of the studs 96, 98 are recessed and reduced, respectively, so that the studs freely telescope with respect to each other as the arm 74 oscillates.

The feeding movement of the feeding members, caused by the spring 94, is under the control of mechanism comprising a cam 102 at the lower front of the machine, this mechanism also being arranged positively to impart the return motion to the feeding members. The cam is fixed to the forward end of a drive shaft 104 which is mounted to rotate in a bearing 106 fixed in the forward part of the frame, and another bearing 108 mounted in the boss 72. The drive shaft may be driven by any suitable means such as a pulley (not shown) fixed to the rear end of the shaft. Arranged to run upon the periphery of the cam 102 is a follower roll 110 which is mounted upon the lower end of a lever 112, the latter being mounted to swing upon a horizontal shaft 114 which is fixed in a pair of lugs 116

formed integral with the frame. The upper end of the lever 112 carries a rounded pin 118 which engages a bearing surface 120 (Fig. 3) on the right-hand side of the arm 14.

The feeding members 18, 20 are shown in Fig. 1 in the position which they occupy at the beginning of a feeding stroke, the roll follower 119 engaging a "higher" part of the cam 102 which rotates in a clockwise direction. When the cam rotates from its illustrated position a falling slope upon it passes the roll 118 allowing the lever 112 to swing counterclockwise under the influence of the spring 94. Thus, a feeding movement is imparted to the feeding members directed toward the left. At the end of this movement a concentric portion of the cam 102 causes a dwell in the movement of the feeding members during which the knife 16 makes a trimming cut through the sole against the anvil 18. Upon completion of the cutting stroke of the knife a rising slope upon the cam 102 causes the lever 112 to be swung clockwise, thereby imparting a positive return stroke to the feeding members.

The knife 16 is fixed to the upper end of a plunger 122 which is mounted to reciprocate vertically in a sleeve 124 formed integral with the frame of the machine. The plunger is driven from the drive shaft 104 through connections comprising roll 126 on a crank pin 127 fixed to the forward surface of the cam 102, and a block 128 which is secured by screws 130 to the lower end of the plunger and is provided with a cam groove 132 in which the roll 126 runs. The lower side of the cam groove 132 has a hump 134, and a conjugate recess 136 is formed in the upper side of the cam groove. The purpose of this shape of the cam groove is to cause a relatively rapid cutting stroke and a slower return stroke. On the completion of the feeding movement of the feeding members, which is about $\frac{1}{8}$ " in extent, the knife 16 will have moved through more than half of its upward stroke and will be close to the bottom of the sole. At this point the above-mentioned dwell in the action of the cam 102 takes place, and the dwell continues while the rounding knife completes its cutting stroke against the upper feeding member 18. The above-mentioned cam groove 132 is so shaped that the rounding knife, after it has penetrated through the work, is eased back very slightly out of contact with the anvil 18. The relatively slow return movement of the knife causes it to remain in the work through a considerable portion of the return stroke of the feeding members during which time the work is also held against any back feeding movement by the gripping action of the presser foot 24 and the work rest 40. It is also during the return movement of the feeding members that the channeling cut is made by the channeling knife 22, the path of the knife being substantially straight because its stroke is so short compared to its radial distance from the axis of the shaft 68 about which it swings.

During each feeding movement of the work the presser foot 24 is moved slightly away from the work rest 40 in order to eliminate any resistance to the feeding of the work by these members. This action of the presser foot is provided by mechanism comprising a cam 138 fixed to the drive shaft 104, a lever 140, and links 142. The cam is provided with a groove 144 arranged to receive a roll follower 146 which is mounted upon the lower end of the lever 140, the latter being arranged to swing in a vertical plane on a pin

148 which is fixed in the frame. The upper ends of the lever 140 and links 142 are pivoted together by a pin 150, and the lower end of each link is provided with an elongated slot 152 which receives a pin 154 carried by an arm 156 formed integral with the above-mentioned arm 34 which carries the presser foot. The purpose of the elongated slots 152 is to permit the presser foot 24 to be lowered, without interference with the pin 154 far enough to permit the work to be presented to the machine.

The cam groove 144 is so shaped as to cause the upper part of the lever 140 and the links 142 to move rearwardly at the beginning of each feeding stroke of the feeding members, the lever and links having a toggle action at this time which forces the arm 156 downwardly. The above described action of the lever and links is reversed at the beginning of each return stroke of the feeding members in order to permit the presser foot to grip the sole against the work rest when the return stroke of the feeding members and the cutting stroke of the channeling knife occur.

The feed foot 20 is readily removable from the arm 14 in order to facilitate the removal of the channeling knife whenever it is to be sharpened. Furthermore, provision is made not only for accurately adjusting the feed foot 20 so as to control the position of the channeling knife with reference to the trimmed sole edge, but also for insuring that the channeling knife and feed foot will, upon being replaced in the machine, be located in their original positions without attention from the operator. The structure just referred to comprises a slide 158 which extends rearwardly from the feed foot and is movable in a slot in the arm 14 which is covered by a plate 159. In the lower side of the slide near its rear end there is a diagonal slot arranged to receive a key 160 which projects upwardly from a bar 162. The bar is mounted to slide crosswise of the machine in a slot formed in the arm 14 and has threaded therein a screw 164 upon the outer end of which a knob 166 is fixed. The screw is mounted to turn, without axial movement, in a pin 168 which is supported by a pair of lugs 170 in such a manner that the bar 162 may be swung downwardly to move the key 160 out of engagement with the slide 158, permitting the feed foot to be freely removed from the arm 14. A spring 172 (Fig. 1) which is received in a hole formed in the arm 14 bears against the lower side of the bar 162, urging the latter constantly about the axis of the pin 168 into engagement with the slide 158. It will now be evident that because of the diagonal key and slot connections between the bar 162 and the slide 158, a fine adjustment of the feed foot and channeling knife, toward or away from the rounding knife, may be effected by turning the knob 166 in the appropriate direction. Moreover, the feed foot upon being replaced in the machine is definitely located in its former adjusted position when the key 160 snaps into the groove in the slide 158 under the influence of the spring 172.

The channeling knife 22 is mounted for vertical adjustment, to vary the depth of the channel which it cuts, in a groove in the rear side of the feed foot 20. The knife is clamped in this groove by a stud 174 having a head which overlies the left-hand edge of the shank of the knife and which is clamped against the knife by setting up a nut 176 which is threaded on the stud within a recess in the forward side of the feed-
ing member.

The use and operation of the machine will now be briefly summarized. The feed foot 20 and the presser foot 24 are first lowered simultaneously by depressing the treadle which is connected to the rod 88. Assuming that the work to be operated upon is a welted shoe having a repair sole temporarily attached to its bottom, the shoe is presented to the machine with the flange 12 and anvil 18 inserted between the sole and the shoe-bottom, and so that the edge of the welt engages the guide 14, the shoe being in its normal upright position. The presser foot and feed foot are now released and hold the sole against the flange 12 and anvil 18, respectively. Upon applying power to the drive shaft 104 the machine acts in a succession of cycles to feed the work step-by-step, and to make one rounding cut and one channeling cut on the sole during each cycle, while the operator holds the shoe and guides it in such a way as to insure that its bottom remains substantially level and in the proper relation with respect to the guide 14, that is to say, in the case of a welted shoe, with the edge of the welt engaging the portion of the guide opposite to the knife-edge.

To explain the operation of the machine it will be sufficient to describe one complete cycle of operation only, such cycle to begin when the feeding members are at the ends of their return stroke, that is, when they are closely adjacent to the flange 12 and presser foot 24. At this time the work is about to be released from the flange 12 by the presser foot, and the knife 16 will have been moved slightly away from the anvil 18. Rotation of the drive shaft will, at this stage, cause simultaneously the completion of the return stroke of the knife and the retraction of the presser foot. As the rounding knife approaches the lower limit of its travel the falling slope of the cam 102 permits the feeding members to move to the left, under the influence of the spring 94, thereby imparting a feeding movement to the work. At the completion of this feeding movement, of about $\frac{1}{16}$ " in length, the rounding knife will have passed through more than half of its cutting stroke and will be close to the bottom of the sole. Now, a dwell in the motion of the feeding members occurs, continuing while the rounding knife completes its cutting stroke. After the rounding knife has penetrated the work it is eased back very slightly out of contact with the anvil 18, and at this time the rising slope on the cam 102 causes the feeding members to be positively moved through their return stroke into proximity to the flange 12 and presser foot 24. During this return movement of the feeding members, the work is gripped between the presser foot 24 and the flange 12 to hold the work against the thrust of the channeling knife which makes its cut at this time. The shoe is further supported against back feeding action by the rounding knife 16 which, because of the slow speed of its return stroke, is not disengaged from the work until after the return movement of the feeding members is completed.

Having described our invention what we claim as new and desire to protect by Letters Patent of the United States is:

1. In a rough rounding and channeling machine, a work rest and an anvil arranged to support continuously in the same plane the sole of a shoe to be rounded, a presser foot and a feed foot opposite to and cooperating with said work rest and anvil, respectively, to grip the sole, a channeling knife associated with said feed foot,

5 said anvil and feed foot being mounted to move together through alternate feeding and return strokes, means for urging said presser foot toward said work rest during the return stroke of said anvil to hold the work against the cutting action of the channeling knife, and a chopping knife cooperating with said anvil to trim the sole edge.

2. In a rough rounding and channeling machine, a work rest and an anvil having work engaging surfaces disposed in the same plane, a carrier for said anvil, a feed foot mounted to swing upon said carrier toward said anvil, means for constantly urging said feed foot toward said anvil, means for oscillating said carrier to cause said anvil and feed foot to be moved together toward and away from said work rest through alternate feeding and return strokes, a channeling knife carried by said feed foot and arranged 10 to make a channeling cut during the return stroke of said anvil and feed foot, a presser foot cooperating with said work rest to hold the shoe against the cutting action of the channeling knife, means for relieving the pressure of said 15 presser foot against the shoe during each feeding stroke of said anvil and feed foot, and a chopping knife cooperating with said anvil to trim the sole edge.

3. In a rough rounding and channeling machine, means for supporting the upper side of a sole to be rounded comprising a fixed work rest and an anvil movable laterally of said work rest through opposite feeding and return strokes, a feed foot arranged constantly to hold the shoe 20 against said anvil, said feed foot also being arranged to move through opposite feeding and return strokes in synchronism with the anvil, a rounding knife operable between successive feeding and return strokes of said anvil to make a 25 trimming cut through the sole against said anvil, a channeling knife carried by said feed foot and arranged to make a channeling cut during the return stroke of said feed foot, a presser foot cooperating with said work rest during the return stroke of said anvil and feed foot to support the shoe against the cutting action of the channeling knife, and means for moving said presser foot away from said work rest during each feeding stroke of said anvil and feed foot.

4. In a rough rounding and channeling machine, an anvil and a work rest arranged to support in a common plane the margin of a sole to be rounded, a knife cooperating with said anvil to trim the sole, a carrier for said anvil, said carrier being movable to cause said anvil 30 to move toward and away from said work rest in said plane, a feed foot arranged to engage the bottom of the sole opposite to the anvil, a channeling knife associated with said feed foot and having a cutting edge directed toward said work rest, an arm on which said feed foot is mounted, said arm being mounted upon said carrier to swing toward and away from said anvil, means for yieldingly urging said arm and carrier away from said work rest to cause said anvil and feed 35 foot to impart a feeding movement to the work, and cam-operated means for controlling the feeding movement of said anvil and feed foot, said cam-operated means being constructed and arranged to impart a positive return movement to said anvil and feed foot between successive feeding movements thereof.

5. In a rough rounding machine, an anvil and a work rest mounted and arranged to support continuously in the same plane, one side of a sole

to be rounded, said anvil being mounted to swing in said plane through alternate feeding and return strokes, a feed foot cooperating with said anvil continuously to grip the sole, a rounding knife movable into engagement with said anvil between its feeding and return strokes to trim the sole, a presser foot mounted and arranged to hold the sole yieldingly against said work rest, and means for retracting said presser foot from the sole during the feeding stroke of said anvil.

6. In a rough rounding machine, means for supporting a shoe to be rounded comprising a work rest and an anvil the work-engaging surfaces of which are disposed at the same level, a chopping knife cooperating with said anvil to trim the sole edge, said work rest comprising a guide arranged to extend across said anvil and to position the shoe crosswise of said knife by engagement with a lateral surface of the shoe, a feed foot cooperating with said anvil to grip the sole continuously, said anvil and feed foot being mounted to oscillate together laterally of said work rest whereby a step-by-step feeding movement is imparted to the work, a presser foot cooperating with said work rest to grip the sole, and means for moving said presser foot away from said work rest during each feeding movement of the work.

7. In a rough rounding machine, feeding means comprising an anvil and a feed foot mounted for movement together about a common axis through alternate feeding and return strokes, means for urging said feed foot toward said anvil to cause a sole to be constantly gripped therebetween, a reciprocatory chopping knife arranged to trim the sole against said anvil, a stationary work rest having a flange arranged to engage the side of the sole engaged by said anvil, the work-engaging surfaces of said flange and anvil being disposed in the same plane, said work rest also comprising a guide extending across said anvil for positioning the shoe toward and away from said knife, a presser foot for yieldingly holding the sole against said flange, and means for moving said presser foot away from said flange during each feeding stroke of said feeding means.

8. In a rough rounding machine, feeding means comprising an anvil and a feed foot, a work rest comprising a flange and a guide arranged to extend across said anvil, said flange and anvil being arranged to project from said edge guide and to be inserted between the bottom of a shoe and the adjacent side of its sole, a carrier for said anvil, said carrier being movable in opposite directions to cause said anvil to move toward and away from said work rest, an arm upon which said feed foot is mounted, said arm being

pivoted upon said carrier to permit said feed foot to swing toward said anvil, means for yieldingly urging said feed foot toward said anvil to cause the sole to be continuously gripped therebetween, a presser foot arranged to engage the bottom of the sole opposite to said work rest, and means acting upon said presser foot intermittently to cause it to grip the sole against said flange between successive feeding movements of said feeding means.

9. In a rough rounding and channeling machine, a work rest and an anvil arranged to support one side of the sole of a shoe at the same level, a presser foot and a feed foot mounted opposite to and arranged to cooperate with said work rest and anvil, respectively, to grip the sole, said anvil and feed foot being mounted to move together through alternate feeding and return strokes, a channeling knife associated with said feed foot and arranged to cut during the return stroke thereof, a chopping knife cooperating with said anvil to trim the sole edge, a slide upon which said channeling knife and feed foot are mounted, said slide being movable crosswise of the edge of the knife to vary the position of the channel relatively to the sole edge, and means for adjusting said slide comprising a member yieldingly engaging said slide and mounted to move away therefrom to free said slide for removal from the machine.

10. In a rough rounding and channeling machine, a work rest and an anvil arranged to support one side of the sole of a shoe at the same level, a presser foot and a feed foot mounted opposite to and arranged to cooperate with said work rest and anvil, respectively, to grip the sole, said anvil and feed foot being mounted to move together through alternate feeding and return strokes, a channeling knife associated with said feed foot and arranged to cut during the return stroke thereof, a chopping knife cooperating with said anvil to trim the sole edge, a slide upon which said channeling knife and feed foot are mounted, said slide being movable crosswise of the edge of the knife to vary the position of the channel relatively to the sole edge, an operator controlled member for adjusting said slide, and tongue and groove connections between said member and slide for transmitting adjusting movement of said member to said slide, said member being mounted to swing away from said slide thereby to separate said connections and to free said slide for removal from the machine.

HAROLD ERNEST ELLIOTT.
